APPARATUS FOR SUPPLYING FLUID-BORNE FLOW OF ABRASIVE MATERIAL

Eugene R. Ziegler, Spencerport, N. Y., assignor to Ritter Company, Inc., Rochester, N. Y., a corporation of Delaware

Application October 1, 1951, Serial No. 249,063

7 Claims. (Cl. 51—12)

1

This invention relates to an apparatus for supplying a fluid-borne flow or stream of abrasive material, such as a current or jet of carbon dioxide carrying finely divided aluminum oxide or the like, as employed, for example, in the dental field for cutting and shaping teeth, one object being to provide an improved apparatus of such character having a more simple, practical and efficient type of construction.

Another object is the provision of such an apparatus adapted to afford a more readily controlled and precisely proportioned mixture of the fluid carrier and abrasives.

Another object is to afford such an apparatus having improved means for stirring and supplying the finely divided abrasive materials to the fluid stream under all conditions of temperature, humidity and the like, as desired for uniformly controlling the proportion of abrasive supplied to the fluid carrier.

A further object is to provide an apparatus of the nature indicated having moving parts of minimum number and weight and capable of operating with a minimum of vibration and noise.

Still a further object is the provision of an apparatus having the above advantages and comprising but few parts of simple construction capable of being readily manufactured and assembled at relatively low cost and of operating with a minimum of attention, interruption of service and maintenance expense.

To these and other ends the invention resides in certain improvements and combinations of parts, all as will be hereinafter more fully described, the novel features being pointed out in the claims at the end of the specification.

In the drawings:

Fig. 1 is a side elevation of an apparatus embodying the present invention;

Fig. 2 is a front elevation;

Fig. 3 is a top plan view;

Fig. 4 is an enlarged sectional plan view on the line 4—4 in Fig. 5 showing parts of the abrasive supply means detached;

Fig. 5 is a further enlarged elevation as viewed from the line 5—5 in Fig. 4;

Fig. 6 is a top plan view of parts shown in Fig. 5 partly broken away;

Fig. 7 is a fragmentary enlargement of parts shown in Fig. 5;

Fig. 8 is a plan view of valve means as seen from line 8—8 in Fig. 7, and

Fig. 9 is a diagrammatic view showing the air and sand conducting lines and valves and controlling electrical connections of the apparatus.

2

The present embodiment of the invention, herein disclosed by way of illustration, provides an apparatus particularly adapted for use by dentists for cutting and shaping teeth by the abrasive action of a jet of gaseous fluid, such as carbon dioxide, air or the like, carrying finely divided abrasive material such, for example, as aluminum oxide, for performing with less pain and discomfort to the patient the operations heretofore accomplished by rotating and vibrating tools such as burrs, drills and the like, as described in Maurer Patent No. 1,664,369.

Referring more particularly to the drawings, the present apparatus comprises a portable casing or cabinet 20 (Figs. 1-3) adapted to be conveniently supported on casters, as 21, for positioning and operation by the side of a dental chair. At the uppermost portion of the casing is a control head 22 with an instrument panel 23 mounting control devices hereafter described and inclined to present the same in conveniently accessible position. From this head extends a flexible conductor 24 having at its free end a hand piece 25 carrying a jet nozzle 26 of suitable construction. A holder 27 may be provided on the cabinet head for releasably supporting the hand piece within reach of the dentist. A suction pipe 28 extends upwardly through an opening in the top 29 of the cabinet in which it is supported for vertical adjustment by a telescopic joint and other known and suitable means, and connected with a filter and a source of reduced pressure as hereafter described. Pipe 28 has its upper portion turned horizontally as at 30 with an open end 31 adapted to be positioned adjacent the mouth of the patient for withdrawing the abrasive and other products of the operation, as disclosed in said Maurer patent.

The fluid carrier for the abrasive material is preferably carbon dioxide supplied from a source of pressure such as the tank 32 (Fig. 9) from which the gas is supplied through a pressure reducer 33 of known and suitable construction at a pressure of say 100 pounds per square inch. The gas passes from the reducer through a pipe 34 to control means by which it may be transmitted in full pressure to the abrasive supplying means, or may be reduced to and transmitted at a lower pressure, as, say, 50 pounds. Such means comprises a pipe 35 leading from pipe 34 to a pipe 36 connected with a valve 37 controlling transmission to the abrasive mixing chamber hereafter described. Pipe 35 leads through a valve 38 controlled by a solenoid device 39, of known and suitable construction, by means of which and its switch, 93, on the instrument panel,

hereafter described, the valve may be moved to position for transmitting the higher pressure, or released for spring actuation to closed position. Connecting with pipe 34 also is a pipe 40 containing a pressure reducer 41 of known and suitable construction by means of which, when valve 38 is closed, the lower fluid pressure is supplied to pipe 36 and the valve 37. Valve 37 has one position for transmitting the carrier gas to the abrasive chamber through a pipe 42, the mixture then passing through pipes 43 and 44 to the hand piece jet, as hereafter more fully described. Valve 37, in its other position, bypasses the mixing chamber and delivers the clean gas to pipe 44 and the operating jet, as desired. Valve 37 is manually operated by a knob 45 on the instrument panel.

The means for supplying the abrasive material to the carrier gas comprises preferably a container in the form of a cylindrical tank 46, Fig. 5, of cast aluminum and suitably supported in fixed position in the cabinet. This container has a removable top closure 47 secured in place by suitable means such as lugs 48 on the container engaged by an interrupted flange 49, as well understood in the art, a gasket such as a resilient sealing ring 50 being interposed to seal the joint. The cover is provided centrally with a hand knob 51 on the upper end of a spindle 52 extending loosely through a relief opening 53 in the cover and carrying a valve disk 54 for engagement with a resilient gasket ring 55 to close the opening. The valve is normally closed under pressure of the contained fluid aided by a compression spring 56 coiled about the spindle and bearing against the valve and against a disk 57 screwed into a flange 58 depending from the cover. The lower end of the spindle is guided in an opening in disk 57 and bears against a filter pad 59 held against the lower end of flange 58 by a cap 60 screwed thereon and provided with openings 61. By depressing knob 51, this valve means may be operated to relieve the pressure in the container when the use of the apparatus is discontinued.

Container 46 has its bottom inclined downwardly towards its center at which it is provided with a threaded orifice plug 62, similarly inclined toward an abrasive discharge orifice 63 leading into a mixing chamber 64 formed in a valve block 65 cast integrally with and depending from the bottom of the container. Extending upwardly through orifice 63 is a gas supply tube 66 of smaller outside diameter than the orifice so as to leave an annular space around it for the discharge of the abrasive material from the container. Tube 66 is fixed at its lower end in a short sleeve 67 secured in a bore in the bottom of block 65, as by means of a tapered threaded fitting 68. Sleeve 67 has openings therein (not shown) for communication with a threaded socket 69 in the block to which the pipe 42 is connected for supplying gas under pressure to the tube 66.

The tube 66 is vibrated laterally, as indicated by the broken lines in Fig. 5, by means hereafter described to agitate and stir the abrasive material and it is preferably provided with a suitable number of lateral outlet openings 70 for producing jets of gas for the same purpose of stirring the material and keeping it in a loose condition for flowing down through orifice 63. The upper end of tube 66 is preferably turned laterally as at 71 to direct the remaining flow of gas into the outlet of a conduit 72 formed in an outwardly projecting rib 73 of the container wall and dis-

charging laterally as at 74 into the mixing chamber 64, to there mix with the abrasive falling through the orifice 63 and driving the mixture through a discharge passageway 75 having at its end a threaded socket 76 for connection with pipe 44 leading to the operating jet nozzle 26.

Means are provided for controlling the discharge of the abrasive through the orifice 63 comprising preferably a cylindrical body 77, of steel or other magnetic material, which is centrally bored to receive tube 66 on which it is fixed just below orifice 63. The upper end of body 77 is roughened, preferably by a series of concentric corrugations, or V-grooves 78 (Figs. 7 and 8), to form ridges inclined outwardly as shown. Such corrugations of the upper surface of the body, in closely spaced parallel relation with the bottom of the container opposite the lower end of the orifice, serves, when the tube is stationary, to obstruct the discharge of the abrasive from the orifice. When the tube is vibrated, however, by means hereafter described, the abrasive is worked outwardly by the corrugations and discharged at the sides of the body 77, so as to maintain a steady flow of the abrasive at a rate substantially proportioned to the amplitude of vibration of tube 66.

The means for vibrating tube 66 comprises preferably an electromagnet indicated generally at 79, Figs. 4 and 5, having a laminated core 80, of generally E-shape, with its energizing coil 81 surrounding the central branch of the core 82, as shown. The outer polar branches 83 and 84 of the core have their ends terminated adjacent the outer walls of the bottom block 65 of the container, as shown, so as to produce a magnetic field extending through the valve body 77. Means are provided for exciting the magnet coil with pulsating direct current and it will be evident that, by varying the impressed voltage, the amplitude of vibration of valve body 77 and tube 66 may be varied, to vary the rate of the flow of abrasive into mixing chamber 64.

A supply of abrasive mixture through pipe 44 to the operating hand piece and its jet 26 is further controlled by a valve 85, Fig. 9, of known and suitable construction, which is operated by a spring actuated solenoid means 86, of known and suitable construction, to either of two positions in one of which the abrasive stream is supplied through conductor 24 to hand piece 25 and its operating jet 26. In the other position of valve 85, the abrasive stream is diverted through a pipe 87 to a filter means or screen 88, of any known and suitable construction, located in the bottom of the cabinet, for removing the abrasive material from the fluid carrier and allowing the latter to escape to atmosphere. When solenoid 86 is energized by means hereafter described, the valve is operated to supply the abrasive stream to the operating jet and when the solenoid is de-energized, to stop the operation, it is actuated by its spring to operate the valve to position to divert the abrasive mixture to the filter as described.

Means are provided for reducing the pressure in pipe 44 whenever valve 38 is closed to reduce the pressure of the gas supplied to the mixing chamber 64, such means preferably comprising a pipe 89 connecting pipe 44 with the filter and including a valve 90 operated by a spring actuated solenoid 91, both of any known and suitable construction. When the solenoid is energized, by means hereafter described, the valve is actuated to vent to atmosphere the excess pressure in

pipe 44, the valve being "loaded" to effect such release at pressures only in excess of the desired lower operating pressure, as well understood in the art. A spring actuated relief valve 92 is provided in pipe 89 between valve 90 and the filter, set to open communication with the filter at pressures above the lower operating pressure for the purpose of relieving excess pressure in the pipe 89 when valve 90 is operated for pressure reduction as described.

The means for effecting such change in the operating pressure comprises preferably the two pole switch 93 having its blade connected, as shown, to one side 94 of the power line. The switch has one pole connected, as shown, to solenoid 89 the other terminal of which is connected by a wire 95 to the other side 96 of the power line. The other pole 97 of the switch is connected by a wire 98 to one terminal of solenoid 91 which has its other terminal connected by a wire 99 with wire 95 and the power line as shown. It will be seen that, by throwing the switch blade to its pole 97, the system will be operated at the lower pressure, while the shifting of the switch to its other position effects operation at the higher pressure. Switch 93 is adjusted to one position or the other by turning a knob 100 on the control panel.

The means for varying the rate of supply of abrasive comprises preferably a half-wave rectifier 101 (Fig. 9), of any known and suitable construction, connected with one side of the power line and with a potentiometer 102 of any known and suitable construction connected with the terminals of the coil of the electromagnet 79. By this means a pulsating direct current is supplied to the electromagnet at a voltage controlled by the adjustment of the potentiometer, as well understood in the art, such voltage being conveniently indicated by a volt meter 103 which may be graduated in any suitable arbitrary units. Adjustment of the potentiometer and the impressed voltage on the electromagnet 79 serves to vary the amplitude of vibration of the tube 66 and valve body 77 and the proportion of abrasive in the carrier stream, described above, as operating conditions may require.

Means are provided for manually controlling the supply of abrasive material and fluid carrier simultaneously, comprising preferably a treadle 104 (Fig. 9) for operating a foot switch 105 having one terminal connected to the side 94 of the power line. The other switch terminal is connected by a wire 106 with the rectifier 101 to start and stop the operation of the abrasive valve means. This terminal of the switch is also connected by a wire 107 with one terminal of the solenoid 86 the other terminal of which is connected by a wire 108 with the other side 96 of the power line. One side of the power line includes a main switch 109 operated by switch lever 110 on the control panel 23. Depression of treadle 104 against the resistance of its spring serves to close the above circuits and start the supply of carrier and abrasive to the operating hand piece jet 26.

As shown in Fig. 1, the filter 88 is positioned in the lower portion of the cabinet 20 and provided with a pipe elbow 111 having a telescopic connection with pipe 28. The filter is connected at its top with the intake of an exhaust fan 112 rotated by an electric motor 113 as shown, the motor having a connection (not shown) with the power line inside the main switch 109. The discharge from the exhaust fan is preferably con-

nected with the space in the cabinet around the filter and discharged through openings (not shown) in the bottom of the cabinet.

The operation of the apparatus has been described above in connection with the description of its construction and may be summarized as follows. The main switch 109 is closed to energize the electrical control means. Switch 93 is adjusted for either high or low pressure, as desired. The abrasive supply valve 37 is turned by means of knob 45 to direct the supply of carrier gas to the material tank and mixing chamber. The rate of supply of the abrasive material is adjusted by adjusting the potentiometer knob 100 on the control panel, thus stirring the abrasive in the container above its discharge orifice and vibrating the valve body 77 to supply the material at the desired rate. To apply the abrasive jet to a tooth, the operator depresses treadle 104, thereby supplying the abrasive stream through the nozzle of the hand piece. To interrupt the operation, treadle 104 is released, thereby quickly diverting the abrasive stream from the hand piece nozzle to the filter pending resumption of the operation, such release of the treadle immediately discontinuing the supply of the abrasive material. The operating pressure may be increased or diminished at any time by corresponding movement of switch 93 which immediately lowers the pressure both in the mixing chamber and in the supply line to the hand piece nozzle when a lower pressure is selected.

It is evident that the invention provides an apparatus by means of which the relative proportions of abrasive and fluid carrier may be readily and accurately controlled, with means for continuously and effectively stirring and agitating the abrasive material to maintain it in a semi-fluid state for discharge through the orifice to the mixing chamber, with minimum interference by conditions of temperature, humidity and the like, to insure uniform mixture in any selected proportion. The proportion of abrasive in the fluid carrier, as well as the pressure of the latter, are subject to accurate and convenient control and the abrasive stream may be quickly started and stopped as the operator may desire. These advantages are obtained by principles of construction involving minimum movement of parts and minimum vibration and noise, as well as a construction of relatively few parts of simple design capable of being readily and economically manufactured and assembled and of being operated with a minimum of interruption of service and of operating expense.

It will thus be seen that the invention accomplishes its objects and while it has been herein disclosed by reference to the details of a preferred embodiment, it is to be understood that such disclosure is intended in an illustrative, rather than a limiting sense, as it is contemplated that various modifications in the construction and arrangement of the parts will readily occur to those skilled in the art, within the spirit of the invention and the scope of the appended claims.

I claim:

1. An apparatus for supplying a fluid-borne flow of abrasive material comprising a container for said material having an orifice adjacent its bottom, a mixing chamber below and communicating with said orifice and having an outlet, a source of fluid under pressure, a movable fluid conduit communicating with said source and extending through said chamber and said orifice adjacent the upper portion of said container,

means providing a fluid duct from the upper portion of said container to said chamber, valve means connected with said conduit for movement thereby to control the flow of said material through said orifice and means for moving said conduit to stir said material in said orifice and container and to actuate said valve means to supply said material to said chamber for mixture with fluid from said duct and discharge through said chamber outlet.

2. An apparatus for supplying a fluid-borne flow of abrasive material comprising a container for said material having an orifice adjacent its bottom, a mixing chamber below and communicating with said orifice and having an outlet, a source of fluid under pressure, a flexible vibratory fluid conduit communicating with said fluid source and extending through said chamber and said orifice adjacent the upper portion of said container, means providing a fluid duct from the upper portion of said container to said chamber, valve means connected with said conduit for vibration thereby to control the flow of said material through said orifice and means for vibrating said conduit to stir said material in said container and to vibrate said valve means to supply said material to said chamber for mixture with fluid from said duct and discharge through said chamber outlet.

3. An apparatus for supplying a fluid-borne flow of abrasive material comprising a container for said material having an orifice adjacent its bottom, a mixing chamber below and communicating with said orifice and having an outlet, a source of fluid under pressure, a flexible vibratory fluid conduit communicating with said source and extending through said chamber and said orifice adjacent the upper portion of said container, means providing a fluid duct from the upper portion of said container to said chamber, valve means in said chamber connected with said conduit for vibration thereby and having a frictionally resistant surface in closely spaced relation to the bottom of said container below said orifice for stationarily obstructing the flow of said material through said orifice, and means for vibrating said conduit to stir said material in said container and to vibrate said valve means to supply said material to said chamber for mixture with fluid from said duct and discharge through said chamber outlet.

4. An apparatus for supplying a fluid-borne flow of abrasive material comprising a container for said material having an orifice adjacent its bottom, a mixing chamber below and communicating with said orifice and having an outlet, a source of fluid under pressure, a flexible vibratory fluid conduit communicating with said source and extending through said chamber and said orifice adjacent the upper portion of said container, means providing a fluid duct from the upper portion of said container to said chamber, valve means in said chamber connected with said conduit for vibration thereby and having a disk-like, circumferentially corrugated surface in closely spaced relation to the bottom of said container below said orifice for stationarily obstructing the flow of said material through said orifice, and means for vibrating said conduit to stir said material in said container and to vibrate said valve means to supply said material to said chamber for mixture with fluid from said duct and discharge through said chamber outlet.

5. An apparatus for supplying a fluid-borne flow of abrasive material comprising a container for said material having an orifice adjacent its bottom, a mixing chamber below and communicating with said orifice and having an outlet, a source of fluid under pressure, a movable fluid conduit extending through said chamber and said orifice adjacent the upper portion of said container, said conduit being formed with lateral outlets for producing fluid jets for stirring said material, means providing a fluid duct from the upper portion of said container to said chamber, valve means connected with said conduit for movement thereby to control the flow of said material through said orifice and means for moving said conduit to stir said material in said orifice and container and to actuate said valve means to supply said material to said chamber for mixture with fluid from said duct and discharge through said chamber outlet.

6. An apparatus for supplying a fluid-borne flow of abrasive material comprising a container for said material having an orifice adjacent its bottom, a mixing chamber below and communicating with said orifice and having an outlet, a source of fluid under pressure, a movable fluid conduit communicating with said source and extending through said chamber and said orifice adjacent the upper portion of said container, means providing a fluid duct from the upper portion of said container to said chamber, valve means connected with said conduit for movement thereby to control the flow of said material through said orifice, a magnetically responsive body connected with said conduit and electric circuit means comprising an electromagnet for moving said body and conduit to stir said material in said container and to move said valve means to supply said material to said chamber for mixture with fluid from said duct and discharge through said chamber outlet, and means for varying the amplitude of movement of said conduit and valve means and varying the supply of said material.

7. An apparatus for supplying a fluid-borne flow of abrasive material comprising a container for said material having an orifice adjacent its bottom, a mixing chamber below and communicating with said orifice and having an outlet, a source of fluid under pressure, a flexible vibratory fluid conduit communicating with said source and extending through said chamber and said orifice adjacent the upper portion of said container, means providing a fluid duct from the upper portion of said container to said chamber, valve means in said chamber connected with said conduit for vibration thereby and having a frictionally resistant surface in closely spaced relation to the bottom of said container below said orifice for stationarily obstructing the flow of said material through said orifice, a magnetically responsive body connected with said conduit, and electric circuit means comprising an electromagnet for vibrating said conduit to stir said material in said container and to vibrate said valve means to supply said material to said chamber for mixture with fluid from said duct and discharge through said chamber outlet, and means for varying the amplitude of vibration of said conduit and valve means and varying the supply of said material.
